UNITED STATES PATENT OFFICE.

CARLOS W. BREWER, OF MINNEAPOLIS, MINNESOTA.

HEATING APPARATUS.

Application filed November 26, 1921. Serial No. 518,034.

To all whom it may concern:

Be it known that I, CARLOS W. BREWER, a citizen of the United States, resident of Minneapolis, county of Hennepin, State of Minnesota, have invented certain new and useful Improvements in Heating Apparatus, of which the following is a specification.

The object of my invention is to provide a heating apparatus which will dispense entirely with the manual stoking of the furnace or boiler and the equally laborious and more disagreeable operation of removing ashes from the furnace.

A further object is to provide an apparatus of the class described which will be positive and reliable in operation, automatically controlled, if desired, and comparatively inexpensive to install.

The invention consists generally in various constructions and combinations, all as hereinafter described and particularly pointed out in the claims.

In the accompanying drawings forming part of this specification,

Figure 1 is a side elevation of a heating apparatus embodying my invention,

Figure 2 is a plan view of the same,

Figure 3 is a detail view of the mechanical stoker, illustrating the controlling mechanism therefor,

Figure 3^a is a detailed view of the switch device and the connected parts,

Figure 4 is a front view of the same,

Figure 5 is a vertical sectional view, showing the firepot in its relation to the walls of the heater and the means for establishing a forced draft therethrough,

Figure 6 is a side view of the suction fan casing connected with the heater.

In the drawing, 2 represents a suitable coal bin, having a hopper bottom 3 leading to a discharge opening 4. 5 is a casing which communicates with the opening 4 to receive the coal by gravity therethrough. In the bottom of this casing is a shaft 6 having a sprocket 7 for a belt 8 on which a series of coal pockets 9 are mounted at substantially uniform intervals in position to scoop up the coal as it is delivered from the bin. This sprocket chain and buckets forming the coal lifting belt are preferably inclined slightly and supported on a similar sprocket wheel 7^a mounted in suitable bearings 10 and having a pinion 11 thereon

connected through a train of gears 12 with the shaft 13 of a suction fan 14 that is driven through a belt 15 from a motor 16 preferably electric. From this construction when the motor is driven the suction fan will be set in motion and through the train of gears the coal buckets will be moved to gather up and lift the coal. A ratchet gear 16^a is preferably mounted on the shaft of the sprocket wheel 7^a and dogs 17 and 18 are provided to engage the teeth of the ratchet and prevent backward movement of the belt. A flue 19 depends within a drum 20 and circulating pipes 21 are arranged within said drum and connected through supply and return pipes 22 and 23 with suitable coils or radiators, not shown, and between these pipes circulating passages or flues 24 are formed for the products of combustion, said passages being so arranged that the products of combustion are compelled to flow in a tortuous manner up and down through the drum between the pipes before reaching the open end of the flue 19 and escaping. I have shown a conventional form of drum with circulating flues or passages, but it will be understood it may be varied in many ways.

At one side of the drum I provide a firebox 25 communicating through a flue opening 26 with the adjacent passage 24 in the drum. In the bottom of this firebox I arrange a gate 26' hinged at 27 and normally closing the lower portion of the box against the discharge of ashes or fuel therein. This box with the gate 26' forms in effect a firepot. Beneath the gate 26' is a discharge pipe 27' through which the ashes descend by gravity to a suitable receptacle 28. In the upper part of the firebox is a gate 29 hinged at 30 and normally extending across the top of the firebox and closing the passage thereto. Both the gates 26' and 29 are normally held in their closed position by springs 31 and 31^a. Above the gate 29 is a pipe 32 having an open top in position to receive the fuel from the fuel buckets as they are inverted in passing around the sprocket wheel 7^a. The delivery of such fuel, however, to the firebox can only take place when the gate is open and the top of the firebox exposed. At such time the fuel resting on the gate 29 will drop by gravity into the firebox beneath upon the gate 26'.

For operating these valves or gates 26' 110

and 29 automatically, I prefer to employ the following described mechanism. 33 is a bell crank, pivoted at 34 on a suitable support 35. One arm of the bell crank projects into the path of a stud 36 on the fuel elevating belt, as indicated in Figure 4. The other arm of the bell crank is loosely connected by a rod 37 with the arm 38 on the gate 26' so that when the elevating fuel belt reaches a predetermined point it will positively open the gate 26' and allow the accumulation of ashes in the firebox to drop down by gravity into the receptacle beneath. As soon as the operating stud passes the bell crank 33, the spring 31 will return the gate to its closed position. A similar bell crank 33^a is provided at a point higher up on the support 35 and also in the path of the stud 36, one arm of the bell crank 33^a being connected by a rod 37^a with a crank 38^a on the upper gate or valve 29 so that when the movement of the fuel belt operates the bell crank 33^a it will positively open the upper gate 29 and allow the accumulation of fuel on this gate to drop into the firebox beneath. As soon as this operation takes place, the gate 29 will be automatically returned to its closed position, shutting off further admission of fuel into the firebox.

Near one side of the firebox I provide a gas burner 39 having a valve 40 of the rotary type positioned to allow a sufficient amount of gas to pass through at all times to form a pilot light and adapted to open through the movement of the crank 41 to a full position and permit the passage of sufficient gas to form a large flame, and project through an opening in the wall of the firebox, and ignite the fuel therein. A bell crank 42 is mounted in the path of the stud 36 and has one arm connected by a rod 43 with the crank 40 so that at a predetermined point in the movement of the fuel elevating belt the gas valve will be opened for a sufficient length of time to ignite the body of fuel in the firebox. The length of time necessary for this purpose will be determined, of course, by experiment and practice, but may be varied under different conditions of fuel and size of the firebox. All this can be determined when the installation is made. A spring 44 is provided for returning the bell crank to its normal position and cutting off a greater portion of the gas when the operating stud is moved to a point where the bell crank 42 is released and the fuel in the firebox has become ignited.

I prefer to provide means for automatically controlling the movement of the motor 16. Suitable conductors 45 and 46 are connected with the motor, one of them extending to the service line and the other to a binding post 47 fixed at some suitable point, preferably on the support 35. A similar conductor 48 leads from the service line to

another binding post 49. Contact springs 50 and 51 are mounted on these binding posts and have end portions for contact with each other to close the circuit between the posts or break the circuit when the springs are separated. Normally, with each complete revolution of the fuel feeding belt the stud 36 will contact with the spring 50 and force it inwardly out of contact with the spring 51, thereby breaking the circuit and stopping the operation of the motor and the feed of the fuel. In some cases, however, it may be desirable for the operator to continue the automatic feeding of the fuel and I therefore mount an arm 52 on the contact spring 51 with a connection 53 leading to an operating motor controlled from a thermostat (not shown) if desired, or having a manual connection through which a pull may be exerted on the connection 53 to tilt it from the full line position in Figure 3 to the dotted line position in the same figure, and thereby force the contact spring inwardly against the surface of the spring 50 and continue the closed circuit and the operation of the fuel feeding apron even after the spring 50 has been compressed inwardly by the passage of the operating stud 36. This controlling mechanism, while shown as an adjunct of my invention, is only auxiliary thereto and may be modified in many ways to accomplish substantially the same results.

I claim as my invention:

1. The combination, with a fire-box, of means for automatically dumping and closing it, means for automatically admitting a fresh supply of fuel thereto when closed, and means for automatically igniting the fresh fuel so delivered. 100
2. The combination, with a fire-box, of means for automatically dumping and closing it, means for automatically admitting a fresh supply of fuel to said box when closed, means for automatically igniting the fresh fuel so admitted, and means for creating a forced draft through said fire-box. 110
3. The combination, with a fire-box, of means for automatically dumping and closing it, a hopper having means for admitting fresh fuel therefrom into said box, means for delivering fresh fuel to said hopper and mechanism for operating said box dumping and closing means and said fuel admitting means successively, and means for automatically igniting the fresh fuel in said box. 115
4. The combination, with a fire-box, of means for automatically discharging the ashes therefrom, a hopper arranged to deliver fresh fuel to said fire-box and means controlled by the delivery of said fresh fuel for automatically igniting the fuel in said box. 120
5. The combination, with a fire-box, of means for automatically delivering a fresh supply of solid fuel thereto and mechanism 130

controlled by the delivery of such fresh supply of solid fuel for automatically igniting said fuel.

6. The combination, with a fire-box having means for discharging ashes, of a hopper having means for admitting fresh fuel to said fire-box, an elevating device for delivering fuel to said hopper, means for automatically igniting the fresh fuel in said hopper, and mechanism actuated through the movement of said elevating device for successively admitting fresh fuel to said fire-box and operating said igniting means.

7. The combination, with a fire-box having a dumping means, and means for delivering fresh fuel thereto, of mechanism for operating said dumping means and said fuel delivery means automatically and successively, and a burner arranged to automatically project a flame into the fresh fuel in said box following the dumping and fuel delivery operations.

8. The combination, with a firebox having means for discharging ashes therefrom and means for admitting fresh fuel thereto, of mechanism for operating said ash discharging means and said fuel admitting

means automatically and successively, a gas burner arranged to automatically project a flame into the fresh fuel in said fire-box, following the discharge of the ashes and the delivery of said fuel to said box. 30

9. The combination, with a fire-box and a heating apparatus connected therewith and a fan for creating a suction through said heating apparatus and said fire-box, of means for automatically dumping said fire-box and delivering fresh fuel to said box and means for subsequently projecting a gas flame into said fuel, for the purpose 40

specified. 10. In combination with a heating apparatus having a tortuous passage therethrough for the products of combustion, a fire-box connected with one end of said tortuous passage, a suction fan connected with the other end of said passage, means for automatically discharging the ashes from said fire-box and admitting fresh fuel thereto, and automatically projecting an igniting flame 50 into said fresh fuel. 45

In witness whereof, I have hereunto set my hand this 23rd day of November 1921.

CARLOS W. BREWER.
